PEPPER DISPENSER OR THE LIKE

George J. Strauss, Los Angeles, Calif.

Application April 21, 1959, Serial No. 55,601

Term of patent 14 years

(Cl. D44—22)

Fig. 1 is a perspective view showing a pepper dispenser or the like embodying my new design;

Fig. 2 is a side elevational view of the same;
Fig. 3 is a top plan view of the same.

I claim:

The ornamental design for a pepper dispenser or the like, substantially as shown.
